Stuart Gwynn

UNITED STATES PATENT OFFICE.

STUART GWYNN, OF NEW YORK, N. Y., ASSIGNOR TO THE AMERICAN METALINE COMPANY, OF SAME PLACE.

IMPROVEMENT IN JOURNAL-BOX LININGS.

Specification forming part of Letters Patent No. **138,643**, dated May 6, 1873; application filed January 29, 1872.

To all whom it may concern:

Be it known that I, STUART GWYNN, of the city, county, and State of New York, have invented a new manufacture, the same being an Improved Lining for Journal-Boxes and other Rubbing-Surfaces, of which the following is a specification, reference being had to the accompanying drawing forming part of the same.

On the 12th day of April, 1870, certain Letters Patent of the United States were issued to me, numbered from 101,862 to 101,869, inclusive, for certain compositions of matter denominated "metaline," and for the process or method of making the same, as also the office it performs, to which reference is made. The invention herein intended to be described and claimed relates to a special mode of applying the said several kinds of metaline or any of them, or their equivalent, to practical use; and consists in a combination of metaline with the material, in the manner and for the purpose particularly described.

Figure 1 is a perspective view, showing the first step in the process of making my improvement. Fig. 2 is a similar view, showing the completed article. Fig. 3 is a similar view of a modification of my invention, the same being a tube formed of sheet metal filled with powdered metaline. Fig. 4 is a similar view of the same tube after the same has been subjected to pressure, and somewhat flattened. Fig. 5 is a similar view of the same cut into halves. Fig. 6 is a similar view of one of said halves after the same has been subjected to still greater pressure, so as to sufficiently consolidate the metaline for use.

In fabricating this article, as shown in Figs. 1 and 2, I take a strip of sheet metal, preferably copper or brass, and bend it, along its whole length, into the form represented, which is the half of a somewhat-flattened tube. This I fill with any one of the varieties of metaline, or their equivalent, described in my said patents of April 12, 1870, that I may elect to use, having reference to the degree of friction to which it is to be subjected in use. Then, by the use of suitable rolls or molds, so constructed as to prevent the escape of the metaline, I subject it to severe pressure upon the sides of the half tube, thereby compressing and consolidating the metaline, as represented in Fig. 2.

It is well, in the act of pressure or otherwise, to turn the upper edges of the sheet in upon the metaline, thereby locking it in; or I use a tube made of sheet metal, filling this with metaline, and flattening it down by pressure into the form shown in Figs. 4, 5, and 6.

It is designed to place a number of pieces of the article side by side a little distance apart within the journal-box, with the open or metaline edges forming a portion of the bearing-surfaces for the journal, which may be done by cutting recesses into the interior face of the box, or in any other suitable manner.

What I claim as a new article of manufacture is—

A sheet of metal, with which is incorporated metaline, substantially as and for the purpose specified.

Witnesses: STUART GWYNN.
